Specification for Design.

Patented Oct. 8, 1912.

Application filed August 23, 1911. Serial No. 645,667. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Deck-Lamp Fixtures, of which the following is a specification.

The nature of my design is fully illustrated in the accompanying drawing to which reference is made, and in which the figure illustrates the design in elevation.

My design comprises a pendant column, the surface of which is curved longitudinally, flaring outwardly in opposite direc-

tions from an intermediate portion, and comprising panels around the periphery of the column, the panels being concave transversely of the pendant, and the bottom portion of the pendant being continued outwardly in symmetrically arranged convex arms having the contour and relative proportion of parts shown.

I claim:

The ornamental design for a deck lamp fixture as shown and described.
